JOHANN KUPKA, OF LONDON, ENGLAND

CAM-OPERATED BALANCED VALVE GEAR FOR STEAM LOCOMOTIVES AND LIKE ENGINES

Application filed June 28, 1926, Serial No. 119,177, and in Great Britain July 24, 1925.

This invention relates to improvements in the distribution valves of steam engines of the balanced poppet or mushroom type in which the valves are operated by cams or tappets. In valve mechanism of this kind, the thrust of the cam or tappet is transmitted directly to the valve stem, or indirectly thereto through intermediate levers, the return movement of the valve being effected by a spring. Inconvenience is sometimes caused in the use of such valve mechanism owing to the breakage of the spring, and an object of this invention is to eliminate the spring from valve mechanism of this kind.

According to this invention, means are provided whereby the valve stem, or a roller thereon, is held in contact with the cam, or with a lever moved by the cam, by the pressure of steam which can conveniently be supplied from the steam generator supplying steam to the engine of which the valves form a part. By thus keeping the valve stem or roller thereon in contact with the part by which it is moved, closure of the balanced mushroom or poppet valve at the required time is ensured without the use of any spring or like metal part. For this purpose a part of the valve stem is arranged to serve in effect as a piston, or a piston is provided to act on the valve stem, in order to move the valve to its closed position.

In the accompanying drawings, which show how the said invention can be conveniently and advantageously carried into practice,

Figure 1 is a sectional view through part of a steam chest showing a steam engine valve arranged in accordance with the invention.

Figures 2, 3, 4 and 5 are similar sectional views respectively illustrating modifications of the arrangement shown in Figure 1.

As shown in Figure 1, 1 is a part of a valve chest with steam passages 2, 3 and a cam chamber 4 formed therein. Communication between these passages is controlled by a valve 5 mounted on a valve stem 6 on which the valve proper is held by nuts 7, allowing the position of the valve to be adjusted on the stem to vary the effective length of the stem, for example, by inserting washers between the hub of the valve and a shoulder 8 formed

on the valve stem against which the valve hub can rest. At the opposite end of the valve stem to that on which the valve 5 is mounted, a roller 9 is rotatably mounted upon the end of the valve stem extending into the cam chamber 4 so as to lie in the path of a cam 10 carried on a cam shaft 11 within the cam chamber. The valve stem is slidably mounted in a sleeve 12 secured in the valve chest and serving also as a guide for the webs 13 of the valve, the sleeve being slotted to provide prongs 14 between which the valve webs 13 can slide, whereby rotation of the valve and its stem is prevented so that the roller 9 is kept in proper position to be acted upon by the cam. The valve stem 6 is made hollow and at an intermediate part of its length apertures 15 are formed to provide free communication between the hollow interior of the valve stem and an annular pocket 16 provided in the said sleeve. Steam is admitted to this pocket through a pipe 15^a from a suitable source so as to maintain a sufficient pressure within the hollow valve stem.

At the end of the valve stem opposite to that acted upon by the cam or tappet, a sliding plunger 17 is provided, forced outwardly from the valve stem by the pressure existing therein, into contact with an abutment 18 on a removable cover plate 19 closing an aperture in the valve chest 1 through which access can be had to the valve. The pressure existing within the hollow valve stem keeps the plunger 17 and the roller 9 at all times in contact with the abutment 18 and the cam 10, respectively, whilst the cam operates through the roller to open the valve, which is returned to its closed position when the cam allows the appropriate movement of the valve stem, the length of which is suitably adjusted with this intention.

In the modified construction illustrated in Fig. 2, the end of the valve stem acted upon by the cam or tappet 10 is arranged as a piston 20 to slide in a sleeve 21 secured in the valve chest 1 and this piston carries a rod 22 guided in a liner 23. The hub 24 of the valve is slidably mounted on the rod 22 and is held thereon in the required position of adjustment between the packing 100

pieces or washers 25 and nut 26. A guide sleeve 27 mounted in a cover plate 28 is provided to prevent rotation of the valve and valve stem. The liner 23 is provided with a collar 29 held between one end of the sleeve 21 and the guide sleeve 27. The valve is closed by the pressure of steam admitted through a port 30 to act upon the effective area of the piston 20, whilst opening of the valve is effected by the cam 10 acting on the roller 9 and thereby moving the rod 22 as required.

In some cases, instead of admitting steam to a space between the valve stem and the sleeve by which it is guided, one end of the valve stem 31, Figure 3, is carried into a liner 32 removably held in a cover plate 33 by a bush 34. Steam is admitted into the liner by a steam pipe 35 and acts upon the valve stem so as to tend to close the valve and keep the valve stem in contact with a lever 36 interposed between a plug 37 at one end of the valve stem and a rotary cam 38, acting through the said lever to effect the opening of the valve. The lever 36 is pivotally supported at 39 and carries a roller 40 to receive the thrust of the cam. As shown in Figure 3, the valve 5 is screwed on the valve stem 31 on which a collar 41 is provided to determine the position of the valve. When the cam is arranged to act on the valve stem through a plug and an interposed lever as shown, a guide to prevent rotation of the valve, such as the prongs 14 in Figure 1, can be dispensed with.

In order to obviate any difficulty which may arise in the use of the arrangement illustrated in Figure 3 owing to want of alignment between the valve stem and the removable cover plate, a separate piston 42, as in Figure 4, can be mounted in the chamber 43 in a removable cover plate 44, to which steam is admitted through a steam pipe 45, this piston abutting against one end of the valve stem 46 which may be formed by a nut 47 holding the valve 5 on the valve stem. The sleeve 12 in which the stem 46 is guided is held in position by a screwed plate 48 and is furnished with valve guides 14.

A similar arrangement to that shown in Figure 4 is illustrated in Figure 5 in which the cam 9 acts on the valve stem 46 through an interposed lever 36.

The cams or tappets for operating the valves can be enclosed in a chamber 4 to which steam can be admitted through an inlet 49, and it is then possible, by suitably controlling the supply of steam to the chamber within the valve stem sleeve, or within the removable cover plate, and the supply of steam to the cam chamber, to provide for maintaining the valve in the open position with the valve stem out of the range of the cam or tappet, or the interposed lever, for example, when the engine is running free as

in the case of a locomotive travelling on a down grade.

It is to be noted that this improved arrangement of valve gear is applicable to stationary and marine engines as well as to locomotive engines.

I claim:

1. Valve actuating mechanism for steam engines, comprising a hollow valve stem having its interior isolated from the valve chest, a piston slidably mounted at one end of said valve stem, a cover plate with which the piston is in contact, a valve associated with said stem, a cam for actuating said valve stem to move the valve into its open position, and means for supplying fluid under pressure into the interior of the valve stem to maintain the end of said valve stem in contact with said cam.

2. Valve actuating mechanism for steam engines, comprising a hollow valve stem having its interior isolated from the valve chest, a piston slidably mounted at one end of said valve stem, a cover plate with which the piston is in contact, a valve associated with said stem, a cam chamber, a cam in said chamber for actuating said valve stem to move the valve into the open position, means for supplying fluid under pressure into the interior of the valve stem to move said valve stem and close the valve, and means for supplying fluid under pressure to said cam chamber for holding the valve open independently of the cam.

3. Valve mechanism for steam engines, comprising a valve, a hollow stem associated with said valve and having its interior isolated from the valve chest, a piston slidable at one end of said valve stem, a cover plate with which the piston is in contact, means for adjusting the position of the valve relatively to the stem, means for supplying fluid under pressure to the interior of the valve stem to move said stem and close the valve, and a cam for opening the valve against the action of the fluid under pressure.

4. Valve mechanism for steam engines, comprising a valve, a hollow valve stem associated with said valve, a cam for opening the valve, a piston slidably mounted at the end of said valve stem remote from the cam, a cover plate with which the piston is in contact, and means for supplying fluid under pressure to the interior of the valve stem to move said stem and close the valve.

5. Valve mechanism for steam engines, comprising a valve, a hollow stem associated with said valve and having its interior isolated from the valve chest, a guide for the valve preventing rotation of the valve about the longitudinal axis of the stem, a piston slidably mounted at the end of said valve stem remote from the cam, a cover plate with which the piston is in contact, means for adjusting the position of the valve relatively

to the length of the stem, means for supplying fluid under pressure to the interior of the valve stem to move said stem and close the valve, and a cam for opening the valve against the action of the fluid under pressure in said valve stem.

5 6. Valve mechanism for steam engines, comprising a valve, a hollow valve stem associated with said valve, a piston slidably mounted at the end of said valve stem remote from the cam, a cover plate with which the piston is in contact, means for varying the effective length of said stem, means for supplying fluid under pressure to the interior of the valve stem to close the valve, and a cam for opening the valve against the fluid under pressure in said valve stem.

10 7. Valve mechanism for steam engines, comprising a valve, a valve stem associated with said valve, a stationary chamber in axial alignment with said valve stem, a piston moving in said chamber and having its head projecting therefrom into contact with the end of the valve stem, means for supplying fluid under pressure to said chamber to move said piston and close the valve, and a cam in contact with the end of the valve stem remote from said piston for opening the valve against the action of the fluid under pressure.

15 8. Valve mechanism for steam engines, comprising a valve, a valve stem associated with said valve, a cover plate, a chamber in said cover plate in axial alignment with said valve stem, a piston moving in said chamber and having its head projecting therefrom into contact with the end of the valve stem, means for supplying fluid under pressure to said chamber to move said piston and close the valve, a cam chamber, a cam in said cam chamber for opening the valve against the action of the fluid under pressure, and means for supplying fluid pressure to said cam chamber for holding the valve open independently of the cam.

JOHANN KUPKA.
